UNITED STATES PATENT OFFICE

149,988

DESIGN FOR A SWEATER

Frank M. Titelman, Altoona, Pa.

Application July 10, 1947, Serial No. 140,189

Term of patent 3½ years

(Cl. D3—4)

To all whom it may concern:

Be it known that I, Frank M. Titelman, a citizen of the United States of America, residing at Altoona, in the county of Blair and State of Pennsylvania, have invented a new, original, and ornamental Design for a Sweater, of which the following is a specification, reference being had to the accompanying drawing, forming a part thereof.

In the drawing—

The drawing shows a front elevational view of a sweater embodying my design, the back body portion of the sweater being plain.

The underneath or back portions of the sleeves are ornamented as shown, the ornamentation being uniformly the same all over the sleeves, except that the cuffs are plain.

I claim:

The ornamental design for a sweater, as shown and described.

FRANK M. TITELMAN.
